INDUSTRIAL TRUCK

Walter S. Nichols, Philadelphia, Pa., assignor to Universal American Corporation, New York, N.Y., a corporation of Delaware
Original application June 8, 1961, Ser. No. 115,652.
Divided and this application June 5, 1962, Ser. No. 200,282

2 Claims. (Cl. 280—43.12)

This invention relates to an industrial truck for handling shipping containers and the like. More particularly, it is concerned with a powered industrial truck having a liftable platform for transporting very heavy loads such, for example, as large so-called "Conex" cases used in shipping military supplies and, when loaded, weighing up to 9,000 pounds; the present application being a division of a prior application Serial No. 115,652, filed by me on June 8, 1961, now abandoned.

The chief aim of the present invention is to provide, in connection with an industrial truck of the kind referred to, mechanism under ready manual control for raising and lowering the platform, which mechanism is economical in power consumption, reliable in operation and resistive to easy derangement over long protracted periods of use.

Other objects and attendant advantages will appear from the following detailed description of the attached drawings, wherein:

FIG. 1 is a view, in side elevation, of an industrial truck with a lift platform and actuating mechanism therefor constructed in accordance with my invention;

FIG. 2 shows the truck in top plan;

FIG. 3 is a fragmentary broken out view drawn to a larger scale and showing the rear end elevation of the truck with its steering handle bar removed, and with certain parts in sections;

FIG. 4 is a fragmentary view in top plan of the frontal end of the truck, with a portion broken out and in section taken as indicated by the angled arrows III—III in FIG. 1;

FIG. 5 is a fragmentary view showing the front end of the truck partly in side elevation, and partly in longitudinal section taken as indicated by the angled arrows V—V in FIG. 3;

FIG. 6 is a view corresponding to FIG. 4 with the load supporting platform of the truck in raised position;

FIGS. 7 and 8 are broken out views partly in elevation and partly in section, taken as indicated by the angled arrows VII—VII and VIII—VIII respectively in FIGS. 4 and 5; and

FIG. 9 is a diagrammatic view showing the power mechanism for raising and lowering the platform.

As exemplified in FIGS. 1-3, the truck has a chassis of which the frame is designated comprehensively by the numeral 1. Mounted on the chassis frame 1 is a housing 3 wherein is enclosed a power plant including an internal combustion engine 4 and a direct-coupled electric generator 5. At the rear, the truck has a carriage 11 provided with a pair of steerable traction wheels 12 which are swingable about vertical pivots engaged in the top platform 77 of said carriage and arranged to be driven by separate electric motors 102 of the reversible field type. The motors 102 are powered by current delivered from the generator 5 through a wiring circuit (not illustrated) controlled by switches which are operable manually by means of grasps 138 on a handle bar 105 by which the truck is steered. The handle bar 105 is pivoted at 106 to the carriage 11 so as to be movable downward from the normal retracted vertical position of FIG. 1 to a more-or-less horizontal position for convenience of the truck user.

With reference now to FIGS. 4-8, the top of the lift platform 10 with which the present application is more particularly concerned, is constructed from suitably stiff

2

plate metal and is downwardly flanged as at 13 and 14 along its opposite side edges. At its rear end, the platform 10 has an upstanding wall 15 likewise fashioned from heavy plate metal with rearwardly bent stiffening flanges 16 and 17 at opposite side edges thereof, and with a rearwardly bent stiffening flange 18 at the top. At its upper corners the wall 15 is provided with lateral projections in the form of rollers 19, 20 which are constrained for guidance within the hollows of vertical guide channels 21 and 22 affixed respectively to winged brackets 23, 24 at opposite sides of the chassis frame 1, said channels being rigidly connected at their tops by a cross beam 25. Underlying the platform 10, somewhat inward of its side edges, are bar levers 26 and 27 which are fulcrumed in clevises 28 and 29 secured to a cross member 30 of a chassis frame 1 at the bottom, and which are fitted at their distal ends with small rollers 31 and 32 that engage the platform from beneath as shown in FIGS. 5 and 6. There is also a relatively wide built up central lever 33 similarly fulcrumed on a pin 34 in lugs 35 on the cross member 30, said lever having spaced side members 36 and 37 spanned by metallic sheeting 38 and being provided with rollers 39 at its distal end for engaging the platform 10 from beneath. Extending crosswise between the levers 26, 27 and 33 approximately midway of their lengths is a rod 40; and arranged in the intervals between the side levers 26 and 27 and the central lever 33 and medially pivoted on said rod, are built up levers 41 and 42 whereof the side members 43, 44 and 45, 46 are connected by a metallic sheeting 47, 48. Pivoted between the distal ends of the side members of the respective levers 47, 48 are small carriages 49, 50 with double floor engaging rollers 51, 52. At their inner ends, the side members 43, 44 and 45, 46 of the levers 41, 42 converge toward each other, and secured between them are ear lugs 53, 54 which are pivotally connected by pins between the ends of horizontal extremities of spaced angle pieces 55, 56 which are welded to or otherwise integrated with the wall 15 of the platform 10 at the back of the said wall. Pivotally connected to swing about the pin 34 is a pair of double-acting pressure-fluid cylinders 61, 62 whereof the piston rods 63, 64 are pivotally connected to a cross pin 65 engaged in lugs 66 welded to or otherwise integrated with the wall 15 of the platform 10 at the back. When the platform 10 is fully lowered normally as in FIG. 5, its front end rests directly upon the rollers 31, 32 and 39 as shown in FIGS. 4 and 5. Elevation of the platform is effected by admitting pressure fluid into the bottoms of the cylinders 61, 62. As the platform 10 rises, a scissor-like action takes place between the levers 26, 27 and 33 and 41, 42 as shown in FIG. 6, with attendant slight rearward tilting of the platform due to lifting of its front end by the rollers 31, 32 and 39 respectively at the distal ends of the levers 26, 27 and 33, and to pivot about the axes of the rollers 19, 20 at the top corners of the wall 15. Admission and exhaust of pressure fluid to and from the cylinders 61 and 62 to raise and lower the platform 10 is controllable manually by means of a three-way valve 67 at the top of a cabinet 68 (FIGS. 1, 2 and 3) positioned centrally of the rear of housing 3 on the chassis 1.

The pressure fluid (which may be oil) used in the cylinders 61 and 62 is drawn, as shown in diagrammatic FIG. 9, through a pipe 179 from a sump 180 supported in the chassis 1 below the enclosure 3 by a pump mounted on said chassis and driven by the motor 5. Leading from the outlet port of pump 9 is a pipe 181 having interposed therein a check valve 182, said pipe extending to a manual control valve 67 whereof the slide 190 is normally maintained centralized by springs 191, 192, the fluid flowing through the bridging portion 193 of valve 67 for return, by way of pipe 195, to the sump 180. The platform lifting cylinders 61 and 62 are connected at their tops by a cross pipe 196 and at their bottoms by a cross pipe 197. Leading

from pipe 196 and extending to the sump 180 is a pipe 198 with an interposed check valve 199; and extending from pipe 197 into the valve 67 at the center is a pipe 200. There is also a branch pipe 203 which leads from pipe 181 at a point ahead of check valve 182 and in which is interposed a relief valve 204. When the platform 10 is to be raised, the operator moves the lever of slide valve 67 to the right as considered in FIG. 9 in consequence of which fluid is delivered under pressure by pump 9 through the piping 181, 188 and pipe 189, and the lefthand port of valve 67, it being finally introduced by way of the piping 200, 197, into the bottom ends of the lift cylinders 61, 62, said cylinders being relieved of fluid from the top at the same time by way of the piping 196, 198 which leads back to the sump 180, during which the check valve 199 automatically opens. Upon release of the lever of valve 67 and return of the slide 190 of said valve to its normal position by the spring 192, the platform is held in raised position by trapping of the liquid beneath the pistons of said cylinders. After the case C has been transported to the desired location, to lower the platform, the operator moves the lever of valve 67 to the left as viewed in FIG. 9, the liquid being thereby allowed to drain from the bottoms of lift cylinders 61, 62 back to the sump 180, by way of the piping 197, 200, the righthand port in the slide of valve 67, and pipe 195. After the platform is lowered, the lever of valve 67 is released by the operator whereupon the slide of said valve is returned to the normal position of FIG. 9 by the spring 191. It is to be understood that, for the most part, the pipe connections and the valves 67, 182 and 204 are all disposed within the housing 3, with the pipes 189 and 195 leading to the control valve 67, the pipe 200 leading externally from said control valve to the cylinders 61 and 62, and the pipe 198 leading from said cylinders to the pump 9.

While in accordance with the provisions of the statutes, I have illustrated and described the best embodiment of my invention now known to me, it will be apparent to those skilled in the art that changes may be made in the forms of the apparatus described without departing from the spirit and scope of the invention as set forth in the appended claims, and that in some cases certain features of my invention may be used to advantage without a corresponding use of other features.

Having thus described my invention, I claim:

1. In an industrial truck, a chassis frame having steerable traction wheels at the rear thereof and means providing opposed laterally spaced upright guide channels at the front thereof, a platform in front of said chassis frame, said platform having an upright wall extending across the rear thereof, a pair of rollers mounted upon said wall for turning freely about a horizontal transverse axis and received respectively by said guide channels whereby to tie together the upper ends of said wall and guide channel means, at least one pair of levers extending longitudinally beneath said platform and interconnected at a point intermediate their ends for pivotal movement of each relative to the other about a horizontal transverse axis, one of said levers being pivotally connected by a rear portion thereof to said chassis frame and being engaged by a front end portion thereof beneath a front end portion of said platform, and the other lever being pivotally connected by a rear end portion thereof to a rear end portion of said platform and having at the distal end thereof floor engaging rollers under a front end portion of said platform, said levers being operative to tie together the lower ends of said wall and guide channel means, and manually controllable power means operatively interposed between said chassis frame and platform and operable for actuating said levers to raise and lower said platform.

2. The combination defined in claim 1 wherein the manually controllable power means includes a pressure fluid cylinder disposed upright between a front end portion of the chassis frame and a rear end portion of the platform, being pivotally connected to both the chassis frame and the platform for movement about horizontal transverse axes.
